Primary Examiner — Paula Allen Greene(74) *Attorney, Agent, or Firm* — Hamre, Schumann, Mueller & Larson, P.C.(57) **CLAIM**

The ornamental design for a headset, as shown and described.

DESCRIPTION

FIG. 1 is a front elevational view of a headset showing my new design.

FIG. 2 is a bottom view of FIG. 1 thereof.

FIG. 3 is a top view of FIG. 1 thereof.

FIG. 4 is a left side view of a portion of FIG. 1 thereof.

FIG. 5 is a right side elevational view of a portion of FIG. 1 thereof.

FIG. 6 is a rear elevational view of FIG. 1 thereof; and,

FIG. 7 is a rear perspective view of FIG. 1 thereof.

1 Claim, 7 Drawing Sheets(56)
